UNITED STATES PATENT OFFICE.

ENEA BOSSI, OF NEW YORK, N. Y., ASSIGNOR, BY MESNE ASSIGNMENTS, TO STEWART-WARNER SPEEDOMETER CORPORATION, A CORPORATION OF VIRGINIA.

VACUUM FEED.

Application filed September 15, 1921. Serial No. 500,808.

To all whom it may concern:

Be it known that J. ENEA BOSSI, a subject of the King of Italy, residing in New York, in the county of New York, State of New York, have invented certain new and useful Improvements in Vacuum Feed, of which the following is a specification.

The present invention relates broadly to fuel feeding systems and more specially to a vacuum feed system.

The principal object of the present invention is to provide a vacuum tank for fuel feed systems of the constantly open type and which is adapted to operate efficiently on both low and high suction.

Another and important object of the present invention is a vacuum tank of the character specified wherein the construction admits of low cost of manufacture.

20 A still further and important object of the present invention is a vacuum tank of the open system type provided with a suction controlled valve of large area adapted to be securely held in place at low suction and to be easily opened at high suction.

25 A still further object of the present invention is a vacuum tank of the character specified and wherein a plurality of relief passageways for the secondary tank extend upwardly between the primary and the secondary tank to vent openings therefor.

30 A still further and important object of the present invention is a valve for controlling the suction conduit, which valve is constructed to admit air to the suction conduit before full opening of the valve occurs.

35 A still further object of the present invention is to provide a primary tank with guiding members in the side walls thereof for the float and so arranged as to provide passageways whereby the incoming supply of fuel may descend beneath the float without impinging upon the upper portion thereof.

40 More specifically, an object of the present invention is a vacuum tank construction of the constantly open type and which is provided with a suction control valve efficient for both high and low suction and with a 45 large outlet leading to the storage tank which is provided with a plurality of vent passageways leading upwardly to open vents considerably above the bottom of the vacuum tank for admission of air to the storage tank.

Other and further objects of the present invention will in part be obvious and will in part be pointed out in the specification following by reference to the drawings forming a part of this application wherein like parts are represented by like characters throughout the several figures thereof.

60 Realizing that the present invention may be embodied in construction other than those herein specifically shown and described it is desired that the disclosure herewith shall be considered as illustrative and not in the limiting sense.

65 Figure 1 is a vertical elevation showing the principal members of the tank in section;

Figure 2 is a section on line 2—2 of Figure 1;

70 Figure 3 is a detail view illustrating the suction controlled valve closed.

75 Figure 4 is a detail view illustrating the suction controlled valve opened slightly to break the partial vacuum in the suction conduit and to permit the valve to be opened as indicated at 5.

80 Figure 5 indicates the suction valve in a full open position.

85 In the vacuum tank art there are three general types or systems defined more specially by the relation of the condition of the tanks to atmosphere. The types comprise; the closed system; the intermittently open system; and the constantly open system. In the constantly open system one of the important problems is the control of the suc-

90 tion passageway, in view of the fact that the suction must be adequate in the primary or vacuum tank to provide a partial vacuum sufficient to raise the liquid fuel, even though the primary tank is constantly open to atmosphere, and at the same time permit the lowering operation of the float to open the valve after the valve has been closed to permit gasoline to feed into the secondary or storage tank.

95 In various types of simple valves heretofore designed the float has necessarily been quite heavy and hollow metallic bodies have ordinarily been employed as floats for this purpose. The manufacture of such floats and the proper weighting thereof is expensive and in view of the enormous quantities of vacuum feed tanks manufactured and sold the fraction of a cent becomes

100 of great importance. Furthermore, heavy floats do not respond quickly to flotation and therefore sometimes permit the primary

105 tank to become partially filled with liquid fuel.

110

tank to fill to a higher level than is desired. If the primary tank becomes overfilled raw gasoline is drawn into the manifold and there is liability of the engine being choked.

5 Furthermore, in vacuum systems heretofore where cylindrical concentric tanks were telescoped it has been customary to provide an annular space between the primary tank and the secondary tank and the gasoline in the

10 secondary or storage tank was liable to splash or rise into this annular space by flowing upwardly and between the cylindrical walls of the annular space by the operation of the vehicle on which the tank was

15 mounted. This not only wasted gasoline, but increased the liability of fire.

The present invention comprises an exceedingly economical construction to manufacture and at the same time overcomes the

20 difficulties of the known art by providing a suction control valve of relatively large area adapted to be securely held in position at low suction and arranged in such manner as to be partially opened to relieve the seating pressure on the valve before the valve is completely opened. This permits the use of a much lighter float than has been heretofore required. One construction for accomplishing this purpose comprises a relatively large disk valve pivoted on a lever arm so as to obtain an increased effect from the weight of the float and constructed in such manner as to slightly tip on the valve seat by a sliding rotary motion, thereby

30 relieving the pressure so that the lever arm may then drop and carry the valve away from the valve seat. In order to permit fuel to feed from the secondary tank by gravity it is necessary that this tank be vented to

40 atmosphere and the venting in the present construction is accomplished by providing a plurality of relatively small independent passageways which extend between the primary tank and the wall of the secondary tank upwardly to vent openings near the top of the secondary tank. One way of obtaining these passageways comprises vertically corrugating the side wall of the primary tank with the maximum diameter of

45 the primary tank comprising substantially the internal diameter of the secondary tank so that when the tanks are telescoped the crests of the corrugations are in contact with the inner wall of the secondary tank.

50 Preferably the secondary tank adjacent the upper portion thereof is provided with a bead, in which bead the vent openings are located. This construction not only provides a plurality of independent vent passageways, but likewise provides guiding ribs which maintain the float in the primary tank spaced apart from the side wall of the tank thereby providing ample space between the float and the wall of the primary tank to permit the incoming gasoline or other

liquid fuel to feed below the float without striking the float from side to side as ordinarily happens in the constructions common in the art. In the present embodiment the primary tank and the secondary tank are

70 sheet metal constructions preferably drawn into cup shape, with the secondary tank provided with screw threads adjacent the upper end thereof and adapted to cooperate with a die cast top whereby rotation of the

75 top causes the screw threaded engagement thereof with the secondary tank to securely lock all of the parts in assembled relation.

Referring now to the drawings for a more detailed description of the construction, the storage or secondary tank 1 is provided with a suitable outlet connection 2 which leads to the carburetor or other fuel feed device (not shown) for a hydrocarbon engine as is common in the art. The secondary tank 1 preferably is provided with a bead 4 in which are arranged vent openings 5 and preferably the wall above the bead 4 is provided with screw threads 6 while the edge of the tank may be finished in any desired manner such as by providing a common folded or wire edge construction 7. The primary tank 8 preferably is provided at its upper end with a flange 9 adapted to set on the wire edge 7 of the storage tank 1.

90 Preferably both tanks are drawn metal constructions and preferably the ordinary side wall of the primary tank 8 is provided with corrugations 10 extending lengthwise of the wall and terminating adjacent the bottom wall 11. The bottom wall 11 carries an outlet valve 12 which preferably is provided with a relatively large outlet passageway 14 closed by a cap valve 15 which preferably is mounted on a weighted lever 16 that is adapted to strike a stop 17 on the lever bracket 18 when the cap valve drops to open position, as indicated in dotted lines, Figure 1, when the primary tank is discharging gasoline into the secondary tank.

100 It is particularly desirable that the primary tank shall discharge quickly and the large weighted cap valve construction has been found both satisfactory and efficient for this purpose.

The cover cap 19 may be formed in different ways and of different materials, and preferably comprises a die casting provided with a depending skirt 20 which is screw threaded on the interior thereof to engage screw threads on the secondary tank. Preferably a gasket 21 of any suitable material is arranged in a groove adjacent the skirt and over the flange 9 on the primary tank so that a hermetic joint is formed when a cover cap 19 is tightly set in position. The top portion of the cover cap 19 preferably is crowned as at 22 and a constantly open vent 24 is provided in the center of the crown. An inlet passageway member 25 is

provided on one side of the crown and preferably terminates in a spout or nozzle 26 adapted to direct incoming gasoline against the side wall of the primary tank 8. This inlet member is adapted to be connected by suitable conduit 27 to the main storage tank (not shown) of an automobile or the like as is common in the art. The cover cap 19, preferably, on the side opposite to the inlet member, is provided with a connection 28 adapted to be connected by means of a suitable conduit 29 to a source of suction, for example, the manifold of a hydrocarbon engine (not shown) as is common in the art.

15 Preferably the connection 28 is provided with a passageway 30 which leads to a valve seat 31. A bracket arm 32 may be integral with the cover cap and preferably depends adjacent the valve seat in such manner as to comprise the fulcrum for a valve operating compound lever. This valve operating lever may be formed of two sections 34 and 35. The section 34 is pivoted to the bracket arm 32 and carries at its forward end a stop 36.

20 The section 35 is pivoted to the section 34 and carries the disk valve 37. When the valve is in position against the valve seat 31 the stop 36 extends over the section 35. The outer end of the compound lever is

25 provided with an opening 38 through which the stem 39 of the float 40 extends. Simplicity of construction is of great importance, as previously stated, in this art, and also reliability and steadiness of construction is imperative. Various types of soldered and screw threaded ends on float stems were tried with varying degrees of satisfaction, but it was found that screw threaded, welded or soldered connections were difficult to make in the limited space, and were expensive as well as being unsatisfactory because of the liability of becoming loosened or broken. The problem was completely solved when it was discovered that a simple hook 41 on the end of the stem 39 could be used providing the float was retained within the primary tank in such manner as to prevent the hook from being disengaged. Preferably the stem 39 is of sufficient length to cause the hook to strike the crowned portion 22 of the cover cap 19 when the primary tank fills with gasoline slightly above a predetermined level. In order to preserve the disk valve 37 from injury and at the same time insure the closing thereof when the float raises, a light coiled spring 42 surrounds the lower end of the stem 39 and sets upon the upper part of the float 40. This spring is adapted to lift the disk valve lever as will later be explained. The float 40 preferably is of a light material such as cork which has been properly treated to prevent the same from becoming soaked and losing its buoyancy. The use of this material is possible in the present device because of the

fact that the construction of the suction control valve is such that a light weight may be utilized to cause the valve to operate.

Assuming the parts to have just reached the position shown in Figure 1 due to the primary tank gradually filling with gasoline. The valve 37 has just closed to cut off the suction and air under atmospheric pressure comes in the vent 24 to overcome the partial vacuum in the primary tank. The weight of fuel in the primary tank will open the cap valve 15 which permits the fuel in the primary tank 8 to quickly flow into the storage or secondary tank 1. This causes the float 40 to move downwardly with the sides of the float being guided by the corrugations 10. During this time the stem 39 passes through the opening 38 without effecting the suction valve because the opening 38 is relatively large and the float is sufficiently controlled or guided as specified so that any contact which the stem may make with the side walls of the opening 39 is very slight and not sufficient to disturb the valve on seat of the suction line. As the gasoline flows into the secondary tank the float continues to descend until the hook 41 strikes the end of section 35 of the compound lever. The further downward movement of the hook causes the section 35 to rotate slightly on the section 34 of the compound lever and this imparts a rotating sliding movement to the disk 37 on the valve seat 31 as is illustrated in Figure 4. When this occurs the side of the disk adjacent the bracket arm 32 acts as a fulcrum point which is very near to the pivot between sections 34 and 35. This provides the relatively great leverage which separates the opposite side of the disk slightly from the valve seat 31, thereby permitting air to rush in over the disk to break the holding effect on the valve and then the further downward movement of the float easily pulls the disk entirely away from the valve seat 31 and parts assume the position shown in Figure 5 with the suction line wide open. This immediately causes a partial vacuum to be formed in the primary tank 8 which closes the cap valve 15 and draws gasoline or the like through tubing 27 to the inlet member 25. The spout 26 directs the flow of liquid fuel against the side wall of the primary tank 8 and this fuel descends through the corrugated passageways past the float 40 into the lower portion of the primary tank. As the primary tank fills with liquid fuel the float 40 rises until the spring 42 encounters the lever arm 35 at which time the arm is raised into contact with the stop 36 and the disk valve 37 is gradually raised toward the valve seat 31. As the disk valve approaches the valve seat suction through the passageway 30 quickly draws the disk into contact with the valve seat and in view of the fact that the disk

- is mounted on the compound lever the parts are so constructed that the disk automatically seats itself in position to completely shut off suction. In view of the relatively 5 large area of the disk valve the pressure holding the disk on the seat is relatively great and therefore the valve disk 37 is securely held in position under low suction conditions.
- 10 Having thus described my invention, what I claim is:
1. In a vacuum fuel feed system, the combination of a vacuum tank, a suction conduit leading to said vacuum tank, a valve seat on the end of said conduit, a disc valve adapted to be held against said seat by atmospheric pressure when a partial vacuum exists in said conduit, a lever for operating said valve, and a light weight float having 15 a free movement within predetermined limits and being adapted to operate said lever to rock said disc on the valve seat when the float lowers beyond the said limits and to cause said disc to drop away from 20 the valve seat to open the suction conduit.
  2. In a vacuum fuel feed system, the combination of a vacuum tank, a suction conduit leading to said vacuum tank, a valve seat on the end of said conduit, a valve 25 adapted to be held against said seat by atmospheric pressure when a partial vacuum exists in said conduit, a lever for operating said valve, and a float having a free movement within predetermined limits and 30 being adapted to operate said lever when the float lowers beyond the said limits.
  3. In a vacuum fuel system, the combination of a constantly open vented vacuum tank, a suction conduit leading to said 35 vacuum tank, a valve seat provided on the end of said conduit, a valve adapted to be held against said seat by atmospheric pressure, a compound lever to rock said valve on said seat and to cause said valve to fall 40 away from said seat, and a float adapted to operate said compound lever.
  4. In vacuum fuel system, the combination of a vacuum tank, a suction conduit leading to said vacuum tank, a valve seat 45 provided on the end of said conduit, a valve adapted to be held against said seat by atmospheric pressure, a compound lever for operating said valve, and a float adapted to 50 operate said compound lever.
  5. In a vacuum fuel feed system, the combination of a primary tank, a suction conduit leading to said primary tank and having 55 a valve seat thereon, a control valve for said conduit, and means for tilting the valve to introduce air into said conduit and back of the valve before the valve leaves the valve seat.
  6. In a vacuum fuel feed system, the combination of a primary tank, a suction conduit leading to said primary tank and having 60

ing a valve seat thereon, a control valve for said conduit, and means for tilting the valve to introduce air into said conduit and back of the valve while a portion of the valve is in contact with the valve seat.

70

7. In a vacuum fuel feed system, the combination of a primary tank, a suction conduit leading to said primary tank and having a valve seat thereon, a control valve for said conduit, and means to introduce air 75 into said conduit while a portion of the valve is in contact with the valve seat.

8. A vacuum fuel feed system comprising a primary tank, a suction conduit leading to said primary tank, a valve adapted to close said conduit, said valve having a relatively large area whereby atmospheric pressure exerts a relatively heavy force to seat said valve against said valve seat, and float controlled lever operating means for 80 gradually removing one side of said valve from said valve seat before the valve completely leaves the said seat.

85

9. A vacuum fuel feed system comprising a primary tank, a suction conduit leading to said primary tank, a valve adapted to close said conduit, said valve having a relatively large area whereby atmospheric pressure exerts a relatively heavy force to seat said valve against said valve seat, and lever operating means for gradually removing 90 said valve from said valve seat.

95

10. In a vacuum feed fuel system, the combination of a vacuum tank adapted to be connected with a source of liquid fuel supply, a suction conduit leading to said vacuum tank, said vacuum tank being at all times vented to atmosphere, a valve seat on the end of said passageway, a pivoted lever, a valve pivoted on said pivoted lever, 100 and float controlled means adapted to tilt said valve upon said valve seat when said float descends to a predetermined level.

105

11. A vacuum fuel feed system comprising a vacuum tank, a liquid fuel inlet, a float having vertical movement in said vacuum tank, and means to maintain said float in contact with a portion and out of contact with other portions of the side wall of said tank to permit the liquid fuel to 110 feed into said tank without pouring down upon said float.

115

12. A vacuum fuel feed system comprising a vacuum tank, a float having vertical movement in said vacuum tank, and vertically extending guide members for contacting with the side of said float and to maintain the same in contact with a portion and out of contact with another portion of the side wall of said tank.

120

13. In a vacuum fuel feed system, a substantially cylindrical storage tank in combination with a vacuum tank shorter than the storage tank and having an exterior diameter substantially equal to the internal diam- 125

130

eter of said storage tank and telescoped within said storage tank, and a passageway leading into the storage tank and formed by a portion of the side wall of said storage tank and a portion of the side wall of said vacuum tank, said passageway leading to a vent for said storage tank.

14. In a vacuum fuel feed system, a substantially cylindrical storage tank in combination with a vacuum tank having an exterior diameter substantially equal to the internal diameter of said storage tank and telescoped within said storage tank, and a passageway formed by a portion of the side wall of said storage tank and a portion of the side wall of said vacuum tank.

15. In a vacuum feed fuel system, the combination of a relatively long substantially cylindrical storage tank, a relatively short substantially cylindrical vacuum tank whose external diameter is substantially equal to the internal diameter of said storage tank and with the vacuum tank telescoped within the storage tank and a passageway into the storage tank formed by a groove in the side wall of one of said tanks, said passageway leading to a vent in the storage tank.

16. In a vacuum feed fuel system, the combination of a substantially cylindrical storage tank, a substantially cylindrical vacuum tank whose external diameter is substantially equal to the internal diameter of said storage tank and with the vacuum tank telescoped within the storage tank, and a passageway formed by a groove in the side wall of one of the said tanks.

17. In a vacuum feed fuel system, the combination of a storage tank, a vacuum tank having external cross-sectional dimensions substantially equal to the internal cross-sectional dimensions of the storage tank and with the vacuum tank telescoped within the storage tank, and a plurality of vertical passageways extending upwardly between said vacuum tank and said storage tank.

18. In a vacuum feed fuel system, the combination of a substantially cylindrical storage tank, a substantially cylindrical vacuum tank having a diameter substantially equal to the internal diameter of the storage tank and with the vacuum tank telescoped within the storage tank, and a plurality of vertical passageways extending upwardly between said vacuum tank and said storage tank.

19. A vacuum feed fuel system comprising a tank having a bead adjacent the upper end thereof, said bead being provided with vent openings, a vacuum tank having an external cross-sectional dimension and shape substantially equal to the internal cross-sectional dimension and shape of said storage tank, and

a plurality of vertically extending grooves in the wall of said vacuum tank to provide passageways leading from said storage tank to said bead.

20. A vacuum feed fuel system comprising a substantially cylindrical tank having a bead adjacent the upper end thereof, said bead being provided with vent openings, a vacuum tank having an external diameter substantially equal to the internal diameter of said storage tank, and a plurality of vertically extending grooves in the wall of said vacuum tank to provide passageways leading from said storage tank to said bead.

21. In a fuel feed system, the combination of a storage tank, a vacuum tank, a cover member for said vacuum tank, a float within said vacuum tank, guiding means for maintaining said float separated from a portion of the walls of said vacuum tank to provide passageways leading around said float, a fuel conduit adapted to be connected to a source of fuel supply, and means to direct fuel from said conduit against the side wall of said vacuum tank and into the passageways between said side wall and said float.

22. A vacuum fuel feed system comprising a vacuum tank, a suction passageway leading to said vacuum tank, a valve seat on said passageway, a valve adapted to fit said seat, a float within said vacuum tank, a stop for limiting the upward movement of said float independently of said spring, and a spring carried by said float and being adapted to gently seat said valve before said stop limits the upward movement of said float.

23. A vacuum fuel feed system comprising a vacuum tank, a suction passageway leading to said vacuum tank, a valve seat on said passageway, a valve adapted to fit said seat, a float within said vacuum tank and having a free movement within predetermined limits, a stop for limiting the upward movement of said float independently of the pressure on the valve, and means adapted to seat said valve before said stop limits the upward movement of said float.

24. A vacuum fuel feed system comprising a vacuum tank, a vertical suction passageway leading to said vacuum tank, a substantially horizontal valve seat on said passageway, a valve adapted to cooperate with said valve seat, a supporting member carrying said valve and adapted to guide the movement thereof, a light float for operating the valve, a float stem member, a connection between said float stem member and said supporting member comprising an opening in one member and a hook formed by bending the end of the other member.
